UNITED STATES PATENT OFFICE.

WILLIAM F. ANKLAM, OF DETROIT, MICHIGAN, ASSIGNOR TO C. M. HALL LAMP COMPANY, OF DETROIT, MICHIGAN, A CORPORATION OF MICHIGAN.

HEADLIGHT.

1,286,197.

Specification of Letters Patent.

Patented Dec. 3, 1918.

Application filed March 16, 1917. Serial No. 155,179.

To all whom it may concern:

Be it known that I, WILLIAM F. ANKLAM, a citizen of the United States of America, residing at Detroit, in the county of Wayne 5 and State of Michigan, have invented certain new and useful Improvements in Headlights, of which the following is a specification, reference being had therein to the accompanying drawings.

10 This invention relates to headlights and refers more particularly to a new and improved construction of headlight adapted for use on automobiles or the like.

15 Among the objects of the invention are to provide a structure whereby an inverted light effect can be obtained in headlight constructions, thus preventing the blinding glare usually produced by headlights having reflectors; to provide a construction in which 20 the deflector is located in front of and centrally positioned with reference to the lamp bulb; to utilize the lamp bulb as a mounting means for the deflector; to provide means whereby the deflector is adjustably supported with respect to the bulb and the reflector; 25 to provide means whereby the deflector can be adjusted toward or from the reflector independent of the adjustment of the bulb with reference to the reflector; to provide a 30 construction in which the light can be focused by adjustment of the deflector alone; and in general to provide a new and improved construction of the character above referred to.

35 In the drawings:

Figure 1 is a vertical sectional view through an automobile headlight embodying my invention;

Fig. 2 is a detailed view of the adjusting bolt detached;

Fig. 3 is an end view of the head of the adjusting bolt;

Fig. 4 is an end view of the nut carried by the adjusting bolt;

Fig. 5 is a detail view of the deflector-carrying shell.

Describing in detail the particular embodiment of my invention shown in the drawings, A designates the reflector of an automobile headlight, B the lens and C the 50 electric light bulb having one end D adjustably mounted in the seat E provided at the rear end of the casing. A suitable lead wire G is provided for conducting the current to the bulb.

55 Various attempts have been made to pro-

vide dimmers and other arrangements for dimming or preventing the glare from the headlight. The present invention, however, contemplates an improved construction whereby the headlight itself is arranged to 60 give an inverted light effect, while permitting proper focusing of the light.

In detail this arrangement comprises a deflector H adjustably mounted upon the end I of the bulb. As shown in Fig. 1 the end I 65 of the bulb extends within a metal casing J, which is apertured at J' to permit the insertion of the adjusting bolt K, the latter being so arranged that its head K' is located within the metal casing J. As shown in detail 70 in Figs. 2 and 3, the head K' of the adjusting bolt is serrated to provide projections K''. The space within the metal casing J is filled with cement which when set will prevent the turning of the adjusting bolt. For 75 more securely fastening the metal casing J to the end I of the bulb, the latter is preferably provided with projections I' which interlock into the cement.

80 Telescopically mounted upon the metal casing J is a shell M which carries the deflector plate H. Within the shell M is positioned a nut L having a screw threaded engagement with the bolt K, this nut L being recessed at N, into which recess there extends prongs O struck from the end of the shell M. This arrangement serves to lock the shell M and nut L against independent 85 rotative movement. Therefore when the shell M is rotated it will also rotate the nut 90 L and because of the threaded engagement between the nut and the bolt will adjust the shell and deflector plate toward or from the center of the bulb. A spring P sleeved upon the bolt K and acting against the metal casing J and the nut L serves to hold the parts 95 in close contact. After the shell M and deflector plate H have been adjusted to properly focus the light they can be locked in this position by tightening up the cap nut Q.

100 From the above description it will be obvious that the focusing of the light can be accomplished by adjustment of the deflector plate alone, or if adjustment of the bulb is made at the opposite end the deflector plate can be adjusted to compensate for any relative change in position between the source of light and the reflector. While I have shown the deflector as formed in the segment of a circle, the invention is not limited to this 105 particular construction, and various other 110

changes in the details of construction and arrangements and combinations of parts can be made within the scope of my invention.

The invention also resides in the novel construction of a bulb having a base on both ends, one end being provided with a lead wire and contact necessary to conduct or carry the current to the filament, and the opposite end or base being formed without a contact or lead wire.

What I claim as my invention is:

1. The combination with a headlight including a bulb and a reflector, of a deflector located in front of and carried by the bulb, and means for adjusting the deflector to focus the light from the bulb with reference to the reflector.

2. The combination with a headlight including a bulb and a reflector, of a deflector located in front of and carried by the bulb,

a spring exerting pressure upon the deflector outwardly from the bulb, and an abutment for said spring connected to said deflector and adjustable to vary its distance from the bulb.

3. The combination with a headlight including a bulb and a reflector, said bulb having securing members on its opposite ends by one of which it is mounted in said reflector, telescopic members one of which is secured to the other securing member of the bulb, said members being relatively axially adjustable, a spring within the outer telescoping member bearing at one end thereupon and at the other upon the inner of said members, and a deflector mounted upon the outer telescoping member.

In testimony whereof I affix my signature.

WILLIAM F. ANKLAM.
